UNITED STATES PATENT OFFICE.

JULIAN LAZOWSKI, OF NEW KENSINGTON, PENNSYLVANIA.

RAIL FASTENER.

1,402,507.

Specification of Letters Patent. Patented Jan. 3, 1922.

Application filed October 3, 1921. Serial No. 505,021.

To all whom it may concern:

Be it known that I, JULIAN LAZOWSKI, a citizen of Poland, residing at New Kensington, in the county of Westmoreland and 5 State of Pennsylvania, have invented certain new and useful Improvements in Rail Fasteners, of which the following is a specification.

This invention relates to certain new and 10 useful improvements in rail fasteners and has particular reference to a clamp device for anchoring a rail to a tie.

The primary object of the invention resides in the provision of a clamp device for 15 anchoring a rail to a tie with the clamp device slidably and interlockingly associated with the tie to be retained in rigid engagement with the rail.

With the above general object in view and 20 others that will appear as the nature of the invention is better understood, the invention consists in the novel form, combination and arrangement of parts hereinafter more fully described in connection with the 25 accompanying drawing and in which like characters of reference indicate corresponding parts throughout the several views.

In the drawing,

Figure 1 is a side elevational view of a 30 tie with the rails supported thereon and shown in section,

Figure 2 is a top plan view of the tie with the rails broken away, and with the clamp devices engaging the rails,

35 Figure 3 is a fragmentary longitudinal sectional view of the tie showing the clamp members and anchoring blocks therefor engaging the rail,

Figure 4 is a fragmentary top plan view 40 partially in section, showing one of the clamp devices disengaged from the rail for removal from the tie,

Figure 5 is a detail sectional view similar 45 to Figure 3 showing the manner of removing the clamp device, and

Figures 6 and 7 are perspective views respectively of the rail engaging clamp and the anchoring block.

Referring more in detail to the accompanying drawing, there is illustrated a tie 1 having a cross seat 2 adjacent each end thereof for supporting a rail 3. The tie, at each side of the cross seat is provided with a rectangular recess 4 having the side there- 55 of adjacent the seat 2 centrally cut away to provide inwardly directed shoulders 5 hav-

ing beveled undercut opposite edges 6 as clearly shown in Figure 4.

A rail engaging clamp 7 tapers in directions toward the rail as shown in Figure 4 60 with the opposite edges thereof beveled as at 8, while the bottom face is inclined upwardly as indicated at 9 for engagement with the adjacent base flange of the rail 3. The outer end of the clamp 7 carries a de- 65 pending shoulder 10 for resting upon the bottom wall of the socket 4.

The rail engaging clamp 7 is of a size with respect to the recess 4 as to be readily removable therefrom when the clamp has 70 the shoulder portion 10 positioned substantially midway of the recess as shown in Figure 4, movement of the clamp in the recess in directions toward the rail causing the beveled walls 8 to engage the undercut 75 walls 6 of the shoulders 5 to constitute an interlocking connection between the clamp and the tie with the inclined bottom wall 9 of the clamp engaging the base flange of the rail as shown in Figure 3. When the 80 clamp is moved to engaging position with the rail, the clamping block 11 having beveled side walls 12 is positioned in the outer end of the seat 4 with the opposite beveled walls engaging the beveled wall 4' of the 85 seat and the outer beveled end 10' of the clamp shoulder 10, an anchoring screw 13 passing through an opening 14 in the block 11 and engaging a threaded socket 15 in the tie, the opposite end walls of the block be- 90 ing perpendicular for engagement with the perpendicular end walls of the recess 4. From an inspection of Figure 3, it will be observed that the bottom face of the clamp- 95 ing block 11 is spaced from the bottom wall of the recess 4, the beveled side walls of the block engaging the beveled walls of the recess and clamp providing a binding engagement between the parts for more securely anchoring the clamp to the tie. 100

With the clamps engaging the rail as shown in Figure 3, the same are securely retained in position by the clamping blocks 11 and to remove the rail, the block 11 is first removed and the clamp 7 moved to the 105 full line position shown in Figure 5 and then to the dotted line position, it being unnecessary to shift the clamp to the outer end of the socket in view of the tapering side walls for purposes of removing the 110 same.

While there is herein shown and described

the preferred embodiment of the invention, it is to be understood that minor changes may be made without departing from the spirit and scope of the invention as claimed.

5. What is claimed as new is:

1. A rail fastener comprising a tie having a cross seat and sockets formed in the tie at opposite sides of the seat, the walls of the sockets adjacent the seat being centrally cut away with the opposite walls of the cut away portion being undercut, a rail engaging clamp having forwardly tapering bevel side walls adapted for engagement with said undercut walls and overlying the base flanges of a rail and means for anchoring the rail engaging clamps to the tie, the clamps and anchoring means lying flush with the upper surface of the tie and said clamps being detachable from the tie by partial movements toward the outer ends of the sockets.

2. A rail fastener comprising a tie having a cross seat and sockets formed in the tie at opposite sides of the seat, the walls of the sockets adjacent the seat being centrally cut away with the opposite walls of the cut away portion being undercut, a rail engaging clamp having forwardly tapering bevel side walls adapted for engagement with said undercut walls and overlying the base flanges of a rail, and an anchoring block positioned in the outer end of each socket engaging said clamp for anchoring the same to the tie, the clamps and anchoring means lying flush with the upper surface of the tie and said clamps being detachable from the tie by partial movements toward the outer ends of the sockets.

3. A rail fastener of the type described

comprising a tie having a cross seat and a recess at each side of the seat with the walls of the recess adjacent the seat being centrally cut away to define undercut side walls, a rail engaging clamp having forwardly tapering beveled side walls engaging said undercut walls and means for holding the clamp in engagement with a rail, the clamps and anchoring means lying flush with the upper surface of the tie and said clamps being detachable from the tie by partial movements toward the outer ends of the sockets.

4. A rail fastener of the type described comprising a tie having a cross rail seat and a recess at each side of the seat with the walls of the recess adjacent the seat being centrally cut away, rail engaging clamps slidably mounted in said seats and interlocking with the forward walls thereof when engaged with a rail, the outer ends of the clamps and recesses being beveled, an anchoring block having beveled side walls positioned in the outer end of each seat with the beveled side walls thereof engaging the beveled walls of the clamp and recess and normally spaced from the bottom wall of the recess and means for anchoring the block to the tie to cause a binding engagement between said bevel walls for moving the clamps in directions toward the rail for securely holding the same in position, the clamps and anchoring means lying flush with the upper surface of the tie and said clamps being detachable from the tie by partial movements toward the outer ends of the sockets.

75
In testimony whereof I affix my signature.

JULIAN LAZOWSKI.
